3 Claims

ABSTRACT OF THE DISCLOSURE

An apparatus is provided for winding web material into roll form utilizing a web winder and a drive system including means for effecting a programmed increase in the linear speed of the web from start-up to and not exceeding the rated web winder speed whereby the speed of the traveling web is increased to the maximum desired speed after the roll diameter of the winding web has attained a surface speed equal to the maximum speed of the drive system.

The present invention relates to winding apparatus and, more particularly, is directed to improvements in and relating to web winding apparatus having an adjustable speed drive utilizing a magnetic clutch assembly and a control system associated therewith.

According to the present invention there is provided a web winding apparatus utilizing a drive system and a web winder, including means for effecting a programmed web speed increase from start-up to and not exceeding the rated web winder speed whereby the speed of the traveling web is increased to the maximum desired speed after the roll diameter of the winding web has attained a surface speed equal to the maximum speed of the drive system.

The nature and advantages of the invention will be more clearly understood by the following description, the appended claims, and the several views illustrated in the accompanying drawings wherein like reference characters refer to the same parts throughout the several views and in which:

FIGURE 1 is a schematic representation in perspective of the functioning parts of the salient portions of the winding apparatus together with the electrical control system; and

FIGURE 2 is a block diagram of the drive system of the apparatus of the present invention.

The apparatus herein disclosed in illustration of the invention includes a mandrel 16 axially driven by a suitable motor 17 through adjustable magnetic clutch 18 operatively connected between the motor 17 and mandrel 16. In operation, moving web material 11 is advanced toward roll 12 at a controlled speed by web advancing roller set 13 which includes a driven roll 14 and a non-driven roll 15 that rotates at the same speed as roll 14. Roll 14 is driven by a suitable motor 41 through adjustable magnetic clutch 38 operatively connected between motor 41 and roll 14. The speed of roll 14 is controlled by magnetic clutch 38, through controller 39, and feed-back from tachometer-generator 19. Power is delivered to magnetic clutch 38 upon actuation of relay 40 and start switch 37. Motor 41 operates at constant speed and is energized from the power line as depicted in FIGURE 1 which is connected to a main power switch, not shown.

Roller set 13 is located ahead of mandrel 16 and advances web material 11 to mandrel 16 where it is wound. A tachometer-generator 19 is operatively connected to roll 14, and a tachometer-generator 20 is operatively connected to mandrel 16; each tachometer-generator generates an electrical signal and each such signal is fed through suitable electrical conductors to inverse speed

2

generator 21. Tachometer-generator 19 is characterized preferably by a voltage level proportional to the rotational speed of roll 14 and a direct current output adapted to charge a capacitor unit in the inverse speed generator 21; and tachometer-generator 20 is characterized by an alternating current output.

The inverse speed generator 21 receives the current output signal from each of tachometer-generators 19 and 20 and, in turn, itself provides a voltage output signal that is a function of the ratio of the rotational speed of roll 14 and mandrel 16. The inverse speed generator 21 is a conventional unit known to the trade such as, for example, Inverse Speed Board No. 45S00345-0010 available from the Louis Allis Company, Milwaukee, Wis. The voltage output signal, commonly referred to as a control signal, from inverse speed generator 21 is fed through suitable electrical conductors to tension adjustor 32 which is a voltage divider adapted to select and transmit to clutch voltage controller 22 a portion of the control signal. The function of inverse speed board or generator 21 is to provide a control signal to clutch voltage controller 22 that is inversely proportional to the ratio of the angular speed of mandrel 16 to the angular speed of roller 14; as the radius of roll 12 increases, the speed of mandrel 16 decreases, and to maintain uniform web tension, the signal from inverse speed board 21 increases or becomes greater resulting in greater output from clutch voltage controller 22 to increase the torque of roll 12 accordingly. It is understood, of course, that as the diameter of roll 12 increases, the torque also must be increased in order to maintain uniform or constant tension on the web material. Thus, inverse speed board 21 provides a signal which accomplishes the purpose of increasing torque with web roll radius.

The clutch voltage controller 22 is a conventional unit known to the trade such as, for example, Voltage Controller No. 45S00798-0000 available from the Louis Allis Company, Milwaukee, Wis. The clutch voltage controller 22 is electrically connected between the power source (not shown) and magnetic clutch 18 and controls in a continuous manner the line voltage or power fed to magnetic clutch 18 in direct response to the control signal received from tension adjustor 32 and thereby controls the torque characteristic of roll 12; i.e., magnetic clutch 18 controls the rotation of mandrel 16 and ensures that the torque of roll 12 is only that which is necessary to maintain uniform tension on the web material during the winding operation.

The change in torque requirement associated with acceleration and deceleration of roll 12 is controlled by acceleration-deceleration compensator 31. The acceleration-deceleration compensator 31 is a detector-amplifier electrically connected, as depicted in FIGURE 1, between tachometer-generator 19 and clutch voltage controller 22, and is adapted to detect and transmit to clutch voltage controller 22 a signal proportional to the rate of increase or decrease of the output signal of tachometer-generator 19. During normal winding operation, the acceleration-deceleration compensator 31, responsive to a constant voltage signal from tachometer-generator 19, transmits zero or no bias signal, but provides a signal of sufficient magnitude to clutch voltage controller 22 during acceleration or deceleration of roll 12 adequate either to increase or decrease the torque output from magnetic clutch 18 or roll 12 for maintaining the required degree of tension on the web material 11. The acceleration-deceleration compensator 31 is a conventional unit known to the trade such as, for example, Acceleration-Deceleration Controller No. 45S00575-0000 available from the Louis Allis Company, Milwaukee, Wis. This element functions essentially by monitoring the magnitude of a capacitor therein

charging or discharging current as the voltage that it senses changes with changing speed of the winding roll.

The foregoing describes the web winding apparatus in essentially its most rudimentary form, and the improvement provided by the present invention resides in apparatus features depicted in FIGURE 1 adapted to linearly accelerate the web material 11 to an original web traveling speed, pause and maintain that speed until the winding web diameter is increased sufficiently to provide a surface speed equivalent to the desired higher web traveling speed, and then to accelerate the web traveling speed to the desired higher speed.

The web winding apparatus of the present invention is further characterized by a diameter-sensing potentiometer 36 responsive to the position of lay-on roll 35 in relation to roll 12 for selecting and transmitting a portion of the bias signal from D.C. bias reference supply A. Lay-on roll 35 is rotatably connected to the ends of levers L and L' and the latter each are pivotally connected at P and P', and lever arm L is provided at one end with adjustable arm extension R that interconnects potentiometer 36 and lay-on roll 35. As seen from FIGURE 1, the lay-on roll 35 at the start of normal winding operations is urged towards mandrel 65 by fluid pressure or other suitable means S and S', and the pivoted lever arm L between potentiometer 36 and lay-on roll 35 moves the adjustable arm R to the maximum position, in relation to the resistor unit in potentiometer 36, to provide the appropriate bias signal to close switch 30 in voltage relay means 42 which is connected to control means 43 comprising a potentiometer 44 and a resistor 45. Control means 43 is connected to a suitable D.C. voltage supply B and controller 39 and is adapted to provide an impulse signal which is transmitted to clutch voltage controller 39 upon energizing relay 40 by actuating start switch 37. As winding roll 12 increases in diameter, it causes lay-on roll 35 to move to the left in FIGURE 1 which, in turn, causes the pivoted lever arm L between potentiometer 36 and lay-on roll 35 to vary the position of the adjustable arm R in relation to the resistor unit in potentiometer 36 and increases the magnitude of the bias signal to voltage relay means 42, and the magnitude of the bias signal increases as the diameter or size of roll 12 increases. Magnetic clutch 18 drives roll 12 through speed changer 47.

The bias voltage source or supply such as, for example, source A, etc., depicted in FIGURE 1, may be any of those known to the art, and preferably is a stable and adjustable D.C. source. For convenience and clarity a number of locations or sources are shown in FIGURE 1 but it is understood all may be connected to a common source.

A brief description of the operation of the winding apparatus with reference to FIGURE 1 follows. When the main power switch (not shown) is energized, power is supplied to motors 17 and 41, and start switch 37 is open as is also normally open relay 46 and relay 40.

Upon closing switch 37 to set the apparatus in motion, relay 40 is closed which couples controller 39 to magnetic clutch 38, thus energizing magnetic clutch 38 and placing roller set 13 in operation to advance web 11 as well as cause rotation of tachometer-generator 19. Closing switch 37 also energizes start relay 46 which causes an

hand position and coupling into the system of inverse speed board 21.

The rising voltage from tachometer-generator 19 causes acceleration-deceleration compensator 31 to produce an output voltage which serves as a bias signal to controller 22 to provide for the additional torque required for accelerating roll 12. The output of tachometer-generator 19 and tachometer-generator 20 combine to provide a control signal from inverse speed board 21 which is transmitted to controller 22.

Voltage relay 42 is preferably provided with a suitable dial calibrated to read directly the roll diameter of roll 12, and is preferably manually adjustable, whereby it may be preset at a selected roll diameter which is sufficient to provide the peripheral speed equivalent to the desired web traveling speed. Thus, voltage relay means 42 is in an open position at small diameters of roll 12. While the voltage relay means 42 is open, resistance 45, large in comparison to the resistor in potentiometer 44, is full across its respective line and, accordingly, for a given preset point on the potentiometer 44, the control means 43 cannot provide a change in magnitude of the bias signal to the main drive speed controller 39. As long as resistance 45 is in series circuit, potentiometer 44 is ineffective to provide a bias signal to controller 39.

As the winding roll 12 reaches the diameter corresponding to the pre-set point on relay means 42, the bias signal from potentiometer 36, closes the switch in voltage relay means 42 whereupon resistance 45 in control means 43 is shorted out of the circuit thus permitting potentiometer 44 to transmit a bias signal of correspondingly decreased magnitude to main drive speed controller 39 for obtaining a corresponding increase in web traveling speed to the desired higher web traveling which is easily and adjustably pre-set by potentiometer 44 in control means 43.

The advantages of the present invention will be more fully appreciated by referring to the following illustrative examples in connection with FIGURE 2 in which the symbols represent:

HP_m =Horsepower of drive motor
 N_m =Drive motor speed (r.p.m.) and clutch input speed
 HP_o =Horsepower of outshaft or clutch
 N_o =Clutch output shaft speed (r.p.m.)
 HP_w =Horsepower of winder spindle
 N_w =Winder spindle speed (r.p.m.)
 $N_s=N_m-N_o$ or differential speed
 D_o =Winder core diameter

ILLUSTRATION NO. 1

The power requirement for winding a web at constant tension may be determined from the equation:

$$HP_o = HP_w = K \frac{D}{2} TN_o$$

and assuming a motor speed, N_m , of 1800 r.p.m., an output speed of the magnetic clutch, N_o , of 1600 r.p.m. and a web traveling speed of 1600 ft. per minute, then the power requirement for winding as the winding core diameter, D_o , increases is listed in Table 1 below:

TABLE 1

Diameter	N_m	N_o	N_s	N_w	HP_o	$1+N_s/N_o$	HP_m	Winding speed
D_o -----	1,800	1,600	200	1,600	1x	1 $\frac{1}{2}$	1 $\frac{1}{2}$ x	1,600
$2D_o$ -----	1,800	800	1,000	800	1x	2 $\frac{1}{4}$	2 $\frac{1}{4}$ x	1,600
$4D_o$ -----	1,800	400	1,400	400	1x	4 $\frac{1}{2}$	4 $\frac{1}{2}$ x	1,600
$8D_o$ -----	1,800	200	1,600	200	1x	9	9x	1,600
$16D_o$ -----	1,800	100	1,700	100	1x	18	18x	1,600

output from clutch voltage controller 22 to energize magnetic clutch 18 and start mandrel 16 rotating which, in turn, causes tachometer-generator 20 to rotate and generate a voltage and cause shifting of relay 28 to the left-

ILLUSTRATION NO. 2

Referring to Illustration No. 1, if it is desired to increase the web traveling speed 50%, i.e., from 1600 r.p.m. to 2400 r.p.m., then the power requirement for

winding as the winding core diameter, D_o , increases is listed in Table 2 below:

TABLE 2

Diameter	Nm	N _o	Ns	Nw	HP _o	1+N _s /N _o	HP _m	Winding speed
D_o	1,800	1,600	200	2,400	1.5z	1 $\frac{1}{2}$	1 $\frac{1}{2}$ z	2,400
$2D_o$	1,800	800	1,000	1,200	1.5z	2 $\frac{1}{2}$	3 $\frac{1}{2}$ z	2,400
$4D_o$	1,800	400	1,400	600	1.5z	4 $\frac{1}{2}$	6 $\frac{1}{2}$ z	2,400
$8D_o$	1,800	200	1,600	300	1.5z	9	13 $\frac{1}{2}$ z	2,400
$16D_o$	1,800	100	1,700	150	1.5z	18	27z	2,400

Thus, it is seen from the above tabulation that by increasing the web speed 50%, it is necessary to install new drives, new higher horse power motors and to respeed the rewind spindles to achieve the desired increase. For instance, at $16D_o$ the HP_m from Table 2 is 50% greater than that listed in Table 1.

ILLUSTRATION NO. 3

The power requirement to increase the web winding speed 50% without respeeding the winder spindles, i.e., N_w and N_o do not exceed 1600 r.p.m., as the core diameter, D_o , increases is listed in Table 3 below.

It must be recognized that at a specific programmed line speed increase, the time required from 0 ft./min. to the desired web speed should be at least the time required for the roll diameter to exceed the diameter having a surface speed greater than the maximum speed of the winder drive. With N_w initially 1600 r.p.m., when $1\frac{1}{2}D_o$ is reached, the line speed is then reset to 2400 f.p.m., for at $1\frac{1}{2}D_o$ the roll diameter would have a surface speed potential equal to the maximum speed of the line drive, when N_w is at 1600 r.p.m.

TABLE 3

Diameter	Nm	N _o	Ns	Nw	HP _o	1+N _s /N _o	HP _m	Winding speed
D_o	1,800	1,600	200	1,600	1z	1 $\frac{1}{2}$	1 $\frac{1}{2}$ z	1,600
$1\frac{1}{2}D_o$	1,800	1,600	200	1,600	1.5z	1 $\frac{1}{2}$	1 $\frac{1}{2}$ z	2,400
$2D_o$	1,800	1,200	600	1,200	1.5z	1 $\frac{1}{2}$	2 $\frac{1}{2}$ z	2,400
$4D_o$	1,800	600	1,200	600	1.5z	3	4 $\frac{1}{2}$ z	2,400
$8D_o$	1,800	300	1,500	300	1.5z	6	9z	2,400
$16D_o$	1,800	150	1,650	150	1.5z	12	18z	2,400

Thus, the winding speed may be increased 50% without requiring new higher horse power motors, e.g., compare HP_m to $16D_o$ for Illustration Nos. 1, 2 and 3—18z, 27z, 45 18z, respectively.

What is claimed is:

1. Winding apparatus comprising a rotatable member driven by a drive motor; an adjustable magnetic clutch operatively connected between said rotatable member and the drive motor; advancing means operatively connected to speed control means adapted to advance a web of material to be wound into roll form on the rotatable member; means adapted to transmit motive power to said magnetic clutch responsive to a control signal, tension control means adapted to generate said control signal proportional to the ratio of the rotational speed of the advancing means and the rotatable member, and adjustable

means operatively connected to said speed control means adapted to generate a bias signal proportional to the pe-

ripheral speed of said roll of web material for increasing the speed of said advancing web.

2. Winding apparatus comprising a rotatable member rotatably driven by a drive motor and an adjustable magnetic clutch operatively connected therebetween; advancing means including an adjustable magnetic clutch adapted to advance a web of material to be wound into roll form on the rotatable member; control means operatively connected to said advancing means adapted to transmit motive power to the magnetic clutch thereof responsive to a control signal, adjustable first potentiometric means adapted for generation of said control signal and for electrical connection between a D.C. voltage source and said control means, and second adjustable potentiometric means adapted for electrical connection to a D.C. voltage source in combination with a guide member adapted to contact the outer layer of web material on the rotatable member and to vary the adjustment of said potentiometer as the roll of web material on the rotatable member increases in size for transmitting a bias signal to said first potentiometric means up to a pre-selected value whereupon said first potentiometric means is en-

ergized for transmitting a bias signal to said control means.

3. Winding apparatus according to claim 2 wherein said first and second potentiometric means are interconnected by a switch adapted to be energized by the bias signal from said second potentiometric means for coupling said first potentiometric means directly to the D.C. voltage source for transmitting a bias signal to said control means.
